ROAD ROLLER

Peter Zettelmeyer, Konz-Karthaus, Germany

Application February 19, 1938, Serial No. 191,552
In Germany February 23, 1937

12 Claims. (CL. 94—50)

This invention relates to a road roller with adjustable rolling wheels or rolls. In order to enable the rolls of road rollers to be adjusted to the profile of a road, it is known to make the rolls adjustable. This adjustability brings with it a number of difficulties. Thus for example the driving of the rolls, which is normally effected by means of toothed wheels, becomes inconvenient, because the driving engine is arranged upon the vehicle frame, and the rolls are in an inclined position in relation to this frame. In many constructions this has simply been compensated for within the toothed drive, that is to say, the pinion meshing with the teeth on the roll is mounted fast on the frame of the road roller, and when the position is inclined, the two toothed wheels also take up an inclined position. For clean working of the toothed gearing such an arrangement is unsatisfactory.

It is further desirable that the rolls should adjust themselves automatically in order that they may follow any changes in the profile of the road. If the axle of the rolls is arranged in the usual manner as to be oscillatable about a point, springs must be provided, which impart an initial stress to the axles, so that the rear wheels, equipped with springs in this manner, feel or test the profile of the road. The springs bring with them an undesirable complication of the road roller, and the custom has therefore been adopted of arranging the rolls upon the axle by the aid of a ball-and-socket joint. Such a ball bearing is however expensive to manufacture.

Furthermore all the structures hitherto mentioned also have the disadvantage that in the adjusting of the roll the tire travels sideways to a marked extent upon the road surface, which is undesirable.

According to the present invention the rolls are pivoted to the frame of the road roller at a place located underneath the axle and within the breadth of the tire. The fundamental idea of this suggestion consists in locating the point of rotation for the rolls at a lower level than in the structures hitherto known, since by this means on the one hand in consequence of the intrinsic weight of the road roller as a whole a good automatic adjustment of the rolls is effected, and on the other hand the transverse movement of the tire upon the road surface becomes less, so that the disadvantages occurring owing to the travel in the transverse direction are practically precluded. The transverse rocking of the tire in the upper half of the wheel is greater, but this is of no consequence.

The practical construction is such that for the roll a casing is employed, which is pivotally connected by a joint, such as a bolt, with the frame of the road-roller, and at the same time receives the ring of teeth and the driving pinion of the roll. This arrangement at the same time brings with it the great advantage that the pinion and the ring of teeth are both enclosed. Hence no foreign bodies, such as sand for example, can enter the toothed gearing. With this construction the toothed pinion and the ring of teeth accompany the rocking movement of the roll.

A further feature of the invention therefore consists in the equalization in the drive being located inside the frame of the road roller. In this way are also obviated those disadvantages that occur in those rollers in which the equalization in the drive is effected in the toothed gearing, that is to say, between the pinion and the ring of teeth. In consequence of the adoption of a casing for the rolls there is a simple possibility of arranging a fixing appliance which is attached directly to the casing.

The invention is illustrated by way of example in the accompanying drawings, in which—

Figure 1 is a side elevation view partly in section through a road roller, embodying the invention.

Figure 2 is a transverse section view through the roller of Figure 1.

Figure 3 is a detail view showing in cross section the drive for the rolls.

Figure 4 is a detail view, similar to Figure 3, of a modified construction.

Figure 5 is a plan view of the rear portion of the roller with the drive mechanism.

The road roller comprises a frame 1 which in the front portion is bent upwardly for mounting the front roll 2. The lower portion of the frame consists of longitudinal girders 3 and several transverse beams 4. The steering of the front roll 2 is effected by means of the handle 5, which controls the steering (not shown in detail) by way of a shaft 6.

In the rear portion of the roller is disposed the driving motor 7, driving by way of a gearing 8 the driving shaft 9, on the end of which a small bevel pinion 10 is mounted, meshing with a large bevelled toothed wheel 11. The latter is mounted on a shaft 12, driving the rear rolls 13 and 14 in the manner described hereinafter. The rolls 13 and 14 are linked to the girders. For this purpose two transverse beams 15 similar to the beams 4 are bolted to the frame (Fig. 2). For mounting the rolls 13, 14 the beams 15 are pro-

vided with laterally projecting bearing eyes 16. For each roll 13, 14 a casing 17 is provided, in which the roll is journalled. The supporting is effected by means of an angle 18 and ball bearings 19 and 20. To the casing 17 is bolted in the lower portion a bearing plate 21. This plate has two webs 22 and 23 welded on to it, one at each end, between which the bearing eyes 16 of the frame engage. Joint bolts 24, which are secured 10 in the usual manner by screws or the like, serve to complete the joint.

Inside the casing 17 a large toothed wheel 25 is keyed to the shaft 18. In the teeth of this wheel meshes a pinion 26, as shown in Figure 3, 15 this pinion likewise being located inside the casing 17, preferably, as shown in Figures 1 and 2, at the height of the axle 18 of the roll, and in front of (or even behind) the axle, as seen in the direction of travel. This pinion 26 is cut directly upon a hollow shaft 27, which is supported with ball bearings 28 in the casing 17 and in a lateral extension 29 thereof. Beside the casing 17, 29, is located a brake 30, which is only diagrammatically indicated. The hollow shaft is 25 internally grooved, and a grooved shaft 31 engages slidably therein, this latter shaft being driven by driving shaft 12 of the road roller through the medium of a double joint 32.

The method of working of the rolls, supported 30 and driven in the manner already described, is as follows. If the rolls come on to a rounded or inclined road profile, the casing 17, with the rolls, swings about the bolts 24. The axis about which this tilting movement takes place is located below the axle 18 of the rolls, and in fact as low down as possible, about in the lower half of the radius of the roll, since the lower down this axis is located, the easier is automatic adjustment. In consequence of the low tilting 40 axis only a very slight travel S upon the road surface for a given obliquity of the rolls occurs, whereas if the tilting axis were located at the axis 18 of the rolls, a travel T would be produced with the same obliquity. It is furthermore under some circumstance desirable to arrange the tilting axis, as emphasized in Figure 2, not in the centre of the breadth of the tire but somewhat towards the middle of the road roller as a whole. By this means the returning of the 45 rolls, which takes place at the transitions from a rounded profile to a flat profile, is facilitated, since the torque in consequence of the greater breadth of the tire, looking outwards from the tilting axis, is higher.

50 The toothed wheels 25 and 26 are completely enclosed in the casing 17, so they are protected against dirt, and can be very carefully lubricated. Moreover by employing a low pitch, a good supporting and a comparatively high transmission ratio can be attained within the toothed 55 wheels 25, 26, thus obviating the necessity for providing a high reduction ratio in the gear, so that small stages of speed reduction are here sufficient. This however at the same time involves the torques within the compensating double joint being small, so that here again the stress is diminished, being reduced to practically one half of the stress in the constructions hitherto known.

70 In order to enable the rolls, which can adjust themselves automatically to the road profile and to the irregularities of the road, to be secured in any desired position, a fastening appliance is attached to the casing 17. To the casing an eye 33 is connected by means of a

75 bolt 34 with a threaded spindle 35. Upon this spindle hand wheels 36 and 37 are mounted to left and right respectively. Between the hand wheels and the fixed wall 38 of the frame are provided springs 39. These springs serve to minimize the shocks, when the stroke is fully utilized. In order to obtain a limitation of stroke, sleeves 40 are provided on both parts of the spindle 35. As the roll deflects towards one side, the spring is gradually stressed, until the 10 maximum stress is attained when the hand wheels come into contact with the sleeve. If a locking of the roll is desired, the hand wheels are both rotated on the threads of the spindle towards one another so far that the stroke 15 movement is eliminated in the case of both rolls and the sleeve is pressed against the fixed wall. If adjustability within certain limits is desired for the roll, the hand wheels are rotated so far that the stroke between sleeve and hand wheel 20 is of the desired amount. To avoid shocks in these positions also, the spring is operative as a resilient intermediate member. The adjustment may be effected either uniformly for both 25 wheels or differently for each wheel.

While maintaining the described pivoting of the rolls at a position below the roll axis, it is possible to employ a sort of parallelogram guide for the purpose of obtaining a parallel or almost parallel displacement of the rolls. For this purpose, as Figure 4 shows, the rolls are guided in the upper portion and in the lower portion by links 41 and 42 respectively, of which the upper one is attached to the locking appliance already described, and the lower one to the roll or to a 35 carrier piece 43 thereof. The further connection required under these circumstances of the roll with the frame is obtained by means of a carrier spring 44, which is connected in the usual manner with the roll, and is supported at the 40 other end on a spring bolt 45 on the casing 17. The spring bolt here lies for instance in two lugs 46, which are attached to the lower portion of the casing 17.

A further possibility with this construction 45 consists in making the links 41 and 42 unequal in length, so that within a certain range a uniform trace is ensured, that is to say, in the event of an alteration in the set or inclination of the rolls, or in other words in the adjustability 50 thereof, there is no narrowing or widening of the trace or wheel track.

In this form of construction the adjusting 55 appliance works in the same manner as that previously described. If the upper link is displaced outwards or inwards by the adjusting appliance, the obliquity of the roll changes. A springing of the frame is in this case effected by the spring 44, so that the frame, with the gear, is protected against shocks as in other 60 vehicles. When the suspension springs are deflected the rolls move parallel or approximately parallel, and with the adjusting appliance loose, the adjusting of the wheels also takes place to correspond to the road profile. Holes and irregularities occurring in the road surface are also ascertained and rolled in owing to the transverse adjustability.

Many modifications within the scope of my invention will occur to those skilled in the art; 70 therefore, I do not limit the invention to the specific forms illustrated in the drawings.

What I claim is:

1. A road roller, comprising a frame, adjustable rolls, means rotatably supporting said rolls 75

and having axes extending transversely of said roller, means pivotally connecting the rolls to the frame so that the plane of each roll can tilt, the axes of said pivotal means extending lengthwise of said roller and being located below said transversely extending axes of rotation of the roll and within the breadth of the roll, a casing in which the roll is supported, a joint connecting the said casing with the frame, a wall element rigidly secured to the frame, means mounted on the upper part of the casing for adjusting the inclination of the roll and securing it at its adjusted inclination, the said adjusting means comprising a screw-threaded spindle extending through the said wall element, two internally screw-threaded hand wheels mounted on the spindle, one on each side of the wall element, and two springs coiled round the spindle, each interposed between the wall element and one of the hand wheels.

2. A road roller, comprising a frame, adjustable rolls, means rotatably supporting said rolls and having axes extending transversely of said roller, means pivotally connecting said rolls to the frame so that said rolls may tilt, the axes of said pivotal means extending lengthwise of said roller and being below said transversely extending axes of rotation of said rolls, and within the breadth of said rolls.

3. A road roller, comprising a frame, adjustable rolls, means rotatably supporting said rolls and having axes extending transversely of said roller, means pivotally connecting the rolls to the frame so that said rolls may tilt, the axes of said pivotal means extending lengthwise of said roller and being below said transversely extending axes of rotation of the roll a distance at least one-half the radius of the rolls and within that half of the breadth of the rolls which is nearer to the center line of the vehicle.

4. A road roller, comprising a frame, adjustable rolls, a casing for supporting each roll, a pivotal joint connecting each casing to the frame so that the rolls may be tilted, the axes of said joints being below the axes of rotation of said rolls and within the breadth of said rolls.

5. A road roller, comprising a frame, adjustable rolls, a toothed wheel rigidly connected with each roll, toothed driving pinions meshing with the toothed wheels, a casing enclosing each toothed wheel and supporting each roll, a joint pivotally connecting each casing with the frame so that the rolls may be tilted, the axes of said joints being below the axes of rotation of said rolls and within the breadth of said rolls.

6. A road roller, comprising a frame, adjustable rolls, means rotatably supporting said rolls and having axes extending transversely of said roller, means pivotally connecting said rolls to the frame so that the rolls may tilt, the axis of said pivotal means extending lengthwise of said roller and being below said transversely

extending axis of rotation of said rolls and within the breadth of the rolls, a gear box for driving the rolls, and means for compensating the drive when the inclination of the roll changes, said compensating means being located within the frame between the frame and the gear box. 5

7. A road roller, comprising a frame, adjustable rolls, a toothed wheel rigidly connected with each roll, toothed driving pinions meshing with the toothed wheels, a hollow shaft carrying the toothed pinion, a grooved shaft longitudinally slidable within said hollow shaft, an engine carried by and driving the road roller, and a double joint connecting the grooved shaft with the engine, and means pivotally connecting said rolls to the frame so that the rolls may tilt, the axes of said pivotal means being below the axes of rotation of said rolls and within the breadth of said rolls.

8. A road roller, comprising a frame, adjustable rolls, a casing for supporting each roll, a pivotal joint connecting each casing to the frame so that the rolls may be tilted, the axes of said joints being below the axes of rotation of said rolls and within the breadth of said rolls, and means mounted on the upper part of each casing for adjusting the inclination of the roll it supports and securing it at its adjusted inclination.

9. A road roller, comprising a frame, adjustable rolls, a casing for supporting each roll, a pivotal joint connecting each casing to the frame so that the rolls may be tilted, the axes of said joints being below the axes of rotation of said rolls and within the breadth of said rolls, and means mounted on the upper part of each casing for adjusting the inclinations of the rolls independently of one another and securing them at their respective adjusted inclinations. 40

10. A road roller, comprising a frame, adjustable rolls, a casing for supporting each roll, a pivotal joint connecting each casing to the frame so that the rolls may be tilted, the axes of said joints being below the axes of rotation of said rolls and within the breadth of said rolls, and means mounted on the upper part of each casing for adjusting the inclination of the roll it supports and securing it at its adjusted inclination, and means for adjusting the amplitude of movement of said roll-inclination-adjusting means.

11. A road roller as claimed in claim 2, further characterized in that the pivotal connecting means includes upper and lower parallel links 55 providing a parallel guide means for said rolls.

12. A road roller as claimed in claim 2, further characterized in that the pivotal connecting means includes upper and lower parallel links providing a parallel guide means for said rolls, 60 and spring means interposed between the roll and the frame.

PETER ZETTELMAYER.
